[57] **CLAIM**

The ornamental design for a light and vase standard, as shown and described.

DESCRIPTION

FIG. 1 is a perspective view of a light and vase standard showing my new design. The broken lines are for purposes of illustration only.

FIG. 2 is a front elevation view thereof, the opposite side being a mirror image thereof.

FIG. 3 is a top plan view thereof.

FIG. 4 is a bottom plan view thereof.

FIG. 5 is a side elevational view thereof, the opposite side being a mirror image.

FIG. 1

FIG. 2

FIG. 3

FIG. 4

FIG. 5
